UNITED STATES PATENT OFFICE.

LOVELL H. PAGE, OF NEW HAVEN, CONNECTICUT, ASSIGNOR TO WINCHESTER REPEATING ARMS CO., OF NEW HAVEN, CONNECTICUT, A CORPORATION.

WINDAGE-SIGHT FOR FIREARMS.

1,291,684.

Specification of Letters Patent. Patented Jan. 14, 1919.

Application filed October 16, 1918. Serial No. 258,398.

To all whom it may concern:

Be it known that I, LOVELL H. PAGE, a citizen of the United States, residing at New Haven, in the county of New Haven 5 and State of Connecticut, have invented a new and useful Improvement in Windage-Sights for Firearms; and I do hereby declare the following, when taken in connection with the accompanying drawings and the 10 characters of reference marked thereon, to be a full, clear, and exact description of the same, and which said drawings constitute part of this application and represent, in—

Figure 1 a broken plan view showing the 15 application of one embodiment of my improved windage sight to a standard military rifle.

Fig. 2 a detached view in rear elevation of the vertically adjustable windage slide 20 of my improved sight.

Fig. 3 a broken view in rear elevation of the receiver of the arm with my improved sight shown with its leaf elevated.

Fig. 4 a vertical central longitudinal section on the line 4—4 of Fig. 3.

Fig. 5 a detached view in rear elevation of the slide shown as carrying the windage-member.

Fig. 6 a detached edge view of the windage-member.

Fig. 7 a detached view thereof in elevation.

Fig. 8 a detached plan view of the aperture bushing.

Fig. 9 a view in horizontal section on the line 9—9 of Fig. 5.

Fig. 10 a detached view in rear elevation, of the vertically adjustable windage-slide and oscillating windage-member of one of 40 the modified forms which my improved sight may assume.

Fig. 11 a corresponding view of the slide, with the windage-member removed.

Fig. 12 a detached view in elevation of 45 the windage-member.

My invention relates to an improved windage sight for firearms, the object being to produce a simple, compact, reliable and convenient windage sight of the type in 50 which the leaf has no lateral adjustment.

With these ends in view, my invention consists in a windage sight having certain details of construction and combination of parts as will be hereinafter described and pointed out in the claims.

In carrying out my invention as shown in Figs. 1 to 9 inclusive, I employ an oscillating windage-member 10 shown as anchor-shaped, though this specific form is not essential. Near the lower end of the center line of the said member, I mount a sight-opening in the form of an aperture-bushing 11, the projecting enlarged front end of which enters a horizontal slot 12 formed in the center of the lower end of the elevation-slide 13 which is mounted for vertical adjustment upon the leaf 14 of the sight, the said leaf turning at its lower end on a pivot 15 the ends of which are fixed in the rear ends of two parallel housing-flanges 16 formed integral with and rising above the upper surface of the rear end of the receiver 17 of the arm. The said leaf 14 is provided with a battle-sight aperture ring 18 of ordinary form and is sustained in either of its two positions as shown in Figs. 1, 3 and 4, by means of a flat spring 19 fastened to the receiver by a screw 20.

At its upper end the windage-member 10 is formed with a vertically arranged elongated slot 21 receiving a pin 22 mounted in the slide 13, whereby provision is made for the sliding motion of the upper end of the windage-member, necessary to compensate for its virtual pivoting upon the inner end of the aperture-bushing 11 as the same is moved horizontally in the slot 12 which restricts the bushing to linear horizontal movement. To provide for adjusting the sight for windage the lower ends of the windage-member are bent backward to form operating-flanges 23 by which it is engaged for being swung in one direction or the other. The said member is also provided with an index mark 24 co-acting with a horizontal windage-scale 25 upon the lower edge of the slide 2. To adjust the sight for windage, one or the other of the flanges 23 is engaged for swinging the windage-member 13 in one direction or the other, whereby 100

- the aperture sight 11 is caused to travel in a strictly horizontal line in one direction or the other, the upper end of the windage-member describing what may be called a "link-motion" upon the pin 22 on account of its provision with the clearance slot 21. The same result would be secured by locating the slot 21 in the slide 13 and the pin 22 in the windage-member 10.
- 5 The slide 13 is formed, as shown, upon its rear face, with cuts 26 and 27 for the exposure of the ordinary scales upon the edges of the leaf 14 and the slide is held in any of its vertical adjustments by means of a 10 pawl 28. By my invention, I am enabled by simple means to convert a standard sight of the type in which the leaf is not laterally adjustable, into a standard sight capable of windage adjustment.
- 15 20 In the modified form of my improvement shown in Figs. 10 to 12 inclusive, the oscillating windage-member 29 is pierced on its median line to form a sight-opening 30 in place of the aperture bushing 11 of the construction previously described. The member 29 is also formed with a hole 31 located in line with the sight-opening 30 aforesaid and receiving a forwardly projecting guide-pin 32 entering a transversely arranged 25 30 curved slot 33 in the lower end of the vertically adjustable elevation-slide 34 which may be of any approved construction. The upper end of the member 29 is formed with a vertically arranged slot 35 receiving a 35 pin 36 mounted in the slide 34 and carrying the member 29 which both oscillates and slides upon it. The curvature of the slot 33 is calculated so that it will insure the movement of the sight-opening 30 in a 40 straight horizontal line 2 when the member is swung in either direction. If preferred, the sight-opening may take the form of a V-shaped aperture or notch, the specific character of such opening being immaterial to my invention which is characterized by the employment of an oscillating windage-member furnished with a sight-opening and applied to a vertically adjustable slide in such a manner that when the windage-member is oscillated the sight-opening, whatever its character, will be constrained to move in a straight horizontal line.
- 45 I claim:—
- 50 1. In a windage leaf sight for firearms, the combination with the leaf thereof, of a slide vertically adjustable thereupon, an oscillating windage-member carried by the said slide and furnished with a sight-opening, and means for constraining the oscillating movement of the said member to cause its sight-opening to move in a straight horizontal line.
- 55 60 2. In a windage leaf sight for firearms,
- the combination with the leaf thereof, of a slide vertically adjustable thereupon, an oscillating windage-member carried by the said slide and furnished with a sight-opening, and pin-and-slot connections between the said member and slide, whereby the sight-opening of the said member is constrained to move in a straight horizontal line when the member is oscillated.
- 65 70 75 80 85 3. In a windage leaf sight for firearms, the combination with the leaf thereof, of a slide vertically adjustable thereupon, an oscillating windage-member carried by the said slide and furnished with a sight-opening, pin-and-slot connection between the upper end of the windage-member and the slide to provide for the oscillating and sliding movement of the said member with respect to the slide, and pin-and-slot connection between the lower end of the said slide and member calculated to constrain the sight-opening of the member to straight line horizontal movement.
- 90 95 4. In a windage leaf sight for firearms, the combination with the leaf thereof, of a slide vertically adjustable thereupon, an oscillating windage-member carried by the said slide and furnished with a sight-opening and with two operating-flanges between which the said opening is centered, and means connecting the slide and member whereby the said sight-opening is constrained to move in a straight horizontal line when the member is oscillated.
- 95 100 105 110 115 5. In a windage leaf sight for firearms, the combination with the leaf thereof, of a slide having a horizontal slot and vertically adjustable thereupon, an oscillating windage-member carried by the said slide, an aperture-bushing carried by the said windage-member and entering the horizontal slot in the slide whereby the lower end of the windage-member is confined to horizontal straight line movement when the member is oscillated, and compensatory connection between the upper end of the said member and slide.
- 110 115 120 125 6. In a windage leaf sight for firearms, the combination with the leaf thereof, of a vertically adjustable slide having a horizontal slot and mounted thereupon, an oscillating windage-member, an aperture-bushing mounted in the lower portion of the said member and entering the horizontal slot in the slide, and pin-and-slot connection between the upper portion of the windage-member and the slide to compensate for the confined straight line movement of the said bushing in the said horizontal slot.
7. In a windage leaf sight for firearms, the combination with the leaf thereof, of a slide vertically adjustable thereupon, an anchor-shaped oscillating windage-member

1,291,684

8

carried by the said slide and furnished with a sight-opening, and means for providing compensatory movement for the said member so that when it is oscillated its sight-opening will be restricted to movement in a straight horizontal line.

In testimony whereof I have signed this

specification in the presence of two subscribing witnesses.

LOVELL H. PAGE.
